UNITED STATES PATENT OFFICE.

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS OR SIMILAR ARTICLES.

SPECIFICATION forming part of Design No. 36,315, dated May 12, 1903.

Application filed March 23, 1903. Serial No. 149,208. Term of patent 7 years.

To all whom it may concern:

Be it known that we, EUSTACE CREEES and CHARLES S. COURT, citizens of the United States, residing in the city of Providence, in the county of Providence and State of Rhode Island, have invented and produced a new, original, and ornamental Design for the Handle of a Spoon or Similar Article, of which the following is a specification, reference being had to the accompanying drawings, forming part thereof.

In the drawings, Figure 1 is a view of the obverse side of a spoon-handle embodying our design, and Fig. 2 the reverse side of the same, upon each of which A represents the head and B the shank.

The leading or material feature of the design consists in the ornamental arrangement in relief of the flowers, buds, and foliage of the tea-rose.

On the obverse side, Fig. 1, the outline is defined by the marginal lines 3 3, representing a rose-stalk. The head A is ornamented with an open tea-rose 4, with its stem 5, which branches from the marginal line 3 in the upper part of the shank B. Above the rose 4 projects the leaf 6, forming a pointed termination of the head. Below it on either side of the handle is a leaf 7. In the upper half 30 of the shank B is a full-blown rose 8, branching from the marginal line 3, and above it, on one side, is a leaf 9 upon the stem 10, which

passes behind the rose 8 and joins the marginal line 3 below on the opposite side. In the narrow part of the shank B are the sprays 35 of rose-leaves 11 11. At the base of the handle is a cluster of rose buds and leaves 12.

On the reverse side, Fig. 2, are the marginal lines 13, representing stalks of the tea-rose, from which at various intervals spring 40 buds, leaves, and flowers, which in the head A form a wreath around a central plain surface 14. At the junction of the head A with the shank B is a full-blown blossom 15 upon a stem which branches from the marginal 45 line 13 on one side and terminates in a bud 16 on the opposite side. 17 and 18 are leaves and buds which branch from the lines 13 13. At the base of the handle is a sprig of leaves 19.

It is evident that our design is applicable 50 to the handles of articles other than but similar to spoons.

We claim—

The ornamental design for the handle of a spoon or similar article as herein shown and 55 described.

In testimony whereof we have affixed our signatures in presence of two witnesses.

EUSTACE CREEES.
CHARLES S. COURT.
